CLAIM

The ornamental design for a biometric health device for animals, as shown and described.

DESCRIPTION

FIG. 1 is a bottom front perspective view of an ornamental design for a biometric health device for animals;
FIG. 2 is a top rear perspective view thereof;
FIG. 3 is a front elevation view thereof;
FIG. 4 is a rear elevation view thereof;
FIG. 5 is a right side elevation view thereof;
FIG. 6 is a left side elevation view thereof;
FIG. 7 is a top plan view thereof;
FIG. 8 is a bottom view thereof; and,
FIG. 9 is a bottom front perspective view thereof, showing the attachment element in an open position to expose profile of the attachment element.
